[57] CLAIM

The ornamental design for a telephone base, as shown and described.

DESCRIPTION

FIG. 1 is a front, top and right side perspective view of a telephone base showing our new design;

FIG. 2 is a top plan view thereof;

FIGS. 3 and 4 are respectively front and rear elevational views thereof;

FIGS. 5 and 6 are respectively right and left side elevational views thereof;

FIG. 7 is a bottom plan view of the base of FIG. 1;

FIG. 8 is a front, top and right side perspective view of the base in FIG. 1 with its bottom elements in an alternative position;

FIG. 9 is a left side elevational view of the base shown as in FIG. 8; and

FIG. 10 is a bottom perspective view of the base of FIG. 8.
